To all whom it may concern:

Be it known that I, Alfred A. Curtis, a citizen of the United States, residing at Lima, in the county of Allen and State of Ohio, have invented a new, original, and ornamental Design for a Shoe Sole, of which the following is a specification, reference being had to the accompanying drawing, forming a part thereof.

Figure 1 is a plan view of a shoe sole, showing the new design; and Figure 2 is a section on the line 2—2 thereof.

What is claimed is:

The ornamental design for a shoe sole, substantially as shown.

ALFRED A. CURTIS.
